[57] ABSTRACT

The movement of the lifting hooks from one draw knife to the other is carried out by means of a bendable spring for each lifting hook. The spring is flexed or bowed between two positions to move a lifting hook. Flexing is caused by means of a selector mechanism programmed to move a flexing element. In one case, the flexing element blocks the upward movement of the spring to cause bending. In another case, the flexing element directly causes bending of the spring.

1
JACQUARD MECHANISM

This invention relates to a jacquard machine and, particularly, to a means for displacing lifting hooks into and out of coupling engagement with draw knives.

Jacquard machines are known in which lifting hooks for forming a shed of warps are lowered by means of jacquard needles which are actuated by means of a reciprocating grate. Usually, the jacquard needles are moved into or kept away from the path of grate movement in accordance with a punched card sensed by sensing needles.

Jacquard machines have also been known which do not use a punched card and sensing needles but instead use a selector comprising flexural oscillators, e.g. electrostrictive or magnetostriuctive elements, for operating the lifting hooks. In this case, a mechanical or pneumatic transmission is usually provided between such oscillators and the lifting hooks.

However, the displacing facilities, e.g., coupling means which are used in machines of this kind and which comprise the selector and the transmission mechanism are relatively complicated, take up considerable space and have a number of moving parts and so are fairly likely to be disturbed in operation.

Accordingly, it is an object of the invention to provide a system for moving the lifting hooks of a jacquard machine which is relatively simple.

It is another object of the invention to provide a system for moving the lifting hooks of a jacquard machine which occupies a relatively small space.

It is another object of the invention to provide a system of relatively few parts for moving the lifting hooks of a jacquard machine.

It is another object of the invention to avoid disturbances in the moving of the lifting hooks of a jacquard machine.

Briefly, the invention provides a jacquard machine of generally conventional structure with a plurality of lifting hooks, draw knives and a means for selectively displacing the lifting hooks into and out of coupling engagement with the draw knives in a programmed manner. The displacing means includes an elongated spring which is bowed between a first position with one lifting hook coupled to a respective knife and a second position with the same lifting hook uncoupled from this knife. The spring serves to effect movement of the associated lifting hook between the various selective lifting hook positions on the respective draw knives.

The term "bowed" is used generally to indicate flexure and is not intended to be limited to a simple curve.

The bendable spring is incorporated in a transmission mechanism which connects the spring to a respective lifting hook and cooperates with a selector mechanism which selects the position for the hook. To this end, the spring serves as the connection between the selector mechanism and the transmission mechanism. In order to select a hook for a rising draw knife, the selector mechanism is actuated so that the spring is allowed to remain in one position while the associated lifting hook is engaged upon upward movement of the knife. In order to move the hook to the other knife when rising, the selector mechanism is thereafter actuated so that the spring is flexed into its second position. This causes the lifting hook to move out of the path of the first knife and into the path of the other knife.

2

The bendable spring has been found to act as a very simple coupling element which has no rotating parts. The spring occupies little space and so the overall displacing means takes up little space. This is of advantage when a large number of lifting hooks and associated bendable springs are needed as, for instance, when each or virtually each individual warp yarn of a loom is to be controlled individually. The invention does allow an unrestricted choice of side repeat (repeat in the weft direction).

These and other objects and advantages of the invention will become more apparent from the following detailed description and appended claims taken in conjunction with the accompanying drawings in which:

15 FIG. 1 illustrates a diagrammatic view of a jacquard machine according to the invention used in a loom;

FIG. 2 illustrates a view to an enlarged scale of some of the main items of FIG. 1;

FIGS. 3, 4 and 5 illustrate views to an even larger scale of the selector mechanism, transmission mechanism, a lifting hook and the knives of FIG. 2 in various positions;

FIG. 6 illustrates a perspective view of an associated detail of the connection of a spring to a lifting hook;

25 FIGS. 7, 8 and 8a each views in section of three variants of a selector mechanism according to the invention;

FIGS. 9 and 10 illustrate diagrammatic view of two elements of FIGS. 7, 8 and 8a;

30 FIG. 11 illustrates a modification of the displacing means according to the invention;

FIG. 12 illustrates a double lifting hook useable with the invention;

FIG. 13 illustrates a modified selector mechanism according to the invention;

FIG. 14 illustrates a view of the selector mechanism of FIG. 13 in another position; and

FIG. 15 illustrates a modified selector using tongues as reeds.

40 Referring to FIG. 1, a jacquard machine 1 is disposed immediately above a shed 2 with a loom of conventional structure. The loom comprises a warp beam 11, a breast beam 13 over which warp yarns or threads 12 pass in the direction indicated by an arrow 54 while the machine is in operation, eyes or mails 21 of heddles 23 and a reed 39. Weft yarns are picked into the shed 2 by a gripper shuttle 35 and beaten up by the reed 39 at shed apex or fell 4 to form a cloth (fabric 6). The cloth passes over a cloth take-up roller 15 and a guide roller 17 and is wound on a cloth beam 19.

The jacquard machine 1 has two draw knives 8, 9 which are movable in separate vertical paths for effecting movements of the heddles 23 to form the shed 2. In addition, a downwardly acting tension spring 25 and a lifting hook 14 adapted to be coupled with the knives 8, 9 act on each heddle 23 as shown. The knives 8, 9 are constructed to rise and fall continuously and alternately, and each carries a hook 51, 52 respectively. In the reversal or dead center position shown in FIG. 2 and in the other reversal or dead center position, in which knife 8 is at the top and knife 9 at the bottom, a weft is picked. In this case, the jacquard machine is a double-lift open-shed machine.

55 Referring to FIG. 2, each heddle 23 has a hook 24 at the upper end by which the heddle 23 is suspended in an associated lifting hook 14. In addition, each lifting hook 14 which is a single hook passes through an open-

ing in a stationary board 25' and carries two hooks 26, 27 for selective engagement with the knives 8, 9 as well as a hook 28 at the upper end for selective engagement with one of the two claws 29, 30 disposed on a stationary support beam 31 of the machine 1. The board 25', the claws 29, 30 and the support beam 31 each extend over the entire weaving width of the loom.

In addition, referring to FIGS. 1 and 2, the jacquard machine 1 has a displacing means 16 at the top which serves to connect each lifting hook 14 to one or the other of the knives 8, 9. This displacing means 16 includes a selector mechanism 18 and a transmission mechanism 20.

Referring to FIG. 2, the selector mechanism 18 includes a large number of control elements such as flexing elements 33 each of which is mounted in the support beam 31 at one end 32. Each element 33 has a free bottom end 34 that can be moved left or right, as viewed, via an external field, e.g. an electric or magnetic field or via a change in temperature of the elements 33 by passing a current through each. Thus, each element 33 functions as a movable control element.

The transmission mechanism 20 includes a pair of stationary rails 36, 38 which extend below the beam 31 and extend over the width of the loom. These rails 36, 38 support spaced apart pins 41 on each of which a slide block 41 is slidably mounted between the confines of the rails 36, 38. As shown in FIG. 6, each slide block 41 has a guide 44 in which a bendable elongate spring 43, e.g. a spring strip, is mounted. In addition, a guide slot 60 is provided in the block 41 to slidably receive a lifting hook 14 in a loose relation.

Referring to FIG. 2, the bottom end 45 of each spring 43 is rolled and is rotatably mounted in a part of the machine frame such as a grate or apertured plate 46 which is mounted for reciprocating motion in a vertical direction and extends across the whole weaving width of the loom. The upper end of the spring passes into an opening or slot 40 in the bottom of the beam 31 to abut or be spaced below the bottom end 34 of an element 33.

The selector mechanism 16 serves to move the control elements 33 into a particular position in accordance with a pattern or texture program while the transmission mechanism 20 transmits a movement to the lifting hooks in accordance with the position of the control elements 33.

Operation is as follows:

With the jacquard machine 1 in the position shown in FIG. 2, the hooks 27, 52 couple the lifting hook 14 to the rising draw knife 9. Also, the hook 28 and claw 29 couple the lifting hook 14 with the support beam 13. Shortly before knife 9 reaches its top reversal position, the grate 46 moves into its top position, shown in FIG. 3. Since the control element 33 is in a blocking position in which the slot 40 in the beam 31 is covered, the spring 43 cannot rise in this region and so the spring 43 deflects into the bent position shown in FIG. 3. Consequently, the slide block 41 and the lifting hook 14 are pressed to the right. When the knife 9 reaches the top reversal position, the hook 28 and claw 29 disengage so that the lifting hook 14 moves into the top right position shown in FIG. 3. The gripper shuttle 35 then picks a weft.

Thereafter, the knife 8 rises and knife 9 descends. Because of the tension spring 25, the lifting hook 14 descends with knife 9. When hook 28 is lower than claw

29, the grate 46 returns to its bottom position in which the grate 46 is inoperative as regards sensing the selector 18, spring 43 moving into the straight or extended position shown in FIG. 2. The lifting hook 14 then moves into the "left" position and continues to descend until the hooks 28 and claw 30 engage with one another. The lifter 14 is now in the bottom left position. Before the lifting hook 14 moves into the "left" position, the rising knife 8 passes by the hook 26 so that coupling of the hook 26 and hook 51 cannot occur.

During the descent of knife 9, each element 33 receives a new selection signal, so that the element 33 moves, e.g. into the bent position 33a of FIG. 4, in which position the slot 40 is open.

Shortly before knife 9 reaches the bottom reversal position and knife 8 the top reversal position, grate 46 rises and senses the element 33. Since the element 33 is in the bent position 33a of FIG. 4, spring 43 moves into the top straight or extended position 43a which can be seen in FIG. 4. Lifting hook 14 therefore remains in the bottom left position. Finally, knife 8 reaches the top reversal position and knife 9 the bottom reversal position. The next weft is picked, whereafter the grate 46 and spring 43 move into the bottom inoperative position shown in FIG. 2, the lifting hook 14 staying in the bottom left position.

During the next fall of knife 8 and rise of knife 9, hook 51 passes by the outside of hook 26, with the result that the lifting hook 14 is moved briefly to the right, but snaps back immediately into the bottom left position. Knife 9 meanwhile rises inoperatively.

During the further sensing of the control element 33 by the spring 43 and grate 46, it is assumed that the spring 43 remains in the straight position of FIG. 4, so that lifting hooks 14 remains in the bottom left position. At the next rise of knife 8 and fall of knife 9, the hook 51 engages in the hook 26 and the lifting hook 14 is lifted. Initially, hook 28 disengages from claw 30, but subsequently hook 28 moves past the outside of claw 29 until finally moving over into engagement in claw 29 (FIG. 5).

At the next sensing of element 33 by spring 43, the lifting hook 14 may take up the "left" position, e.g. because of the element 33 being in position 33a. Knife 8 then falls and knife 9 rises. Lifting hook 14 remains in the top left position of FIG. 5, and so on.

As shown in FIG. 3, the hook 27 is shorter than hook 26, so that when the knife 9 is in the bottom reversal position, the hook 27 can move over the hook 52 upon bending of the spring 43 and the lifting hook 14 can be lifted at the next rise of knife 9.

Since the engagement position for the hook 28 and claws 29, 30 is disposed above the displacing movement of the slide block 42, the deflecting movement of the double hook 26, 27 is correspondingly greater. The amount of the latter movement can be varied by appropriate action on the relationship between the distance of the claw 29 or 30 from the slide block 42 and the distance of the slide block 42 from the reversal positions of the double hooks 26, 27.

In the embodiment shown in FIG. 7, it is assumed that the bottom free end 34 of the control element 33 has a foot-shaped protecting cap 53 and that the slot 40 for the spring 43 is closed when the element 33 is in the chain-line deflected position 33a'.

In the example shown in FIG. 8, the slot 40a is in the covered state when the element 33 is in a straight posi-

tion, so that the bent position 43a of the spring 43 occurs during sensing. In this example, the control element 33 has a protective cap 53a.

In the construction shown in FIG. 8a, the control element 33 has a horseshoe-shaped spring 53b adapted to close the slot 40 thus ensuring that there is very little stressing of the element 33 by the spring 43 during sensing.

The slot 40a can have an inclined portion 40b on the "bend" side of the spring 43, if so desired, in which event the spring 43 can virtually engage with the part 49b during bending. The bending force which the grate 46 is required to produce is decreased by this feature.

As shown in FIG. 9, the control element 33 can be e.g. a magnetostrictive element, comprising two strips 67, 69 which expand differently from one another in an applied magnetic field, so that bending occurs. Such field can be produced by means of a winding 71 which can be connected via a switch 72 to a power supply 73 or else can be connected to the appropriate part of a programmer.

In an alternative form, shown in FIG. 10, an electrostrictive (piezoelectric) flexural element 65 is used, in the form e.g. of two strips of different material, the two materials expanding differently when an electric field is applied to the two outer electrodes 73a. Due to the different expansions of the materials, the element takes up a bent position.

In the embodiment shown in FIG. 11, there are two control elements 33, 33b, two bending springs 43, 43b and two lifting hooks 14, 14a disposed symmetrically of one another in the same support member 31. The two elements, springs and lifting hooks can be controlled either synchronously, as shown, or asynchronously. For instance, the element 33 can be in the bent position shown and the element 33b in the straight position, so that spring 43 is in the straight position and spring 43b in the bent position. In such a case, the lifting hook 14 is in the position shown, whereas lifting hook 14b is displaced to the right. This construction requires very little space.

In the embodiment shown in FIG. 12, a double lifting hook 70 having two arms 70a, 70b is guided in a single slide block 42a formed with two guide slots 60, 60a for the arms 70a, 70b. The spring 43 can therefore be used to displace double lifters.

In the variant of FIG. 13, the grate 46 is stationary. The spring 43 is so devised that the inoperative position is the solid-line bent position of FIG. 13. Control element 33 can reciprocate as shown by arrow 85. When the element 33 is in the straight position, upon moving to the left the element 33 strikes the spring 43 to move the spring 43 into the chain-like straight position 43b', in which a motion for displacing the lifting hooks can be derived from the rise of the spring end 50.

If the control element 33 is deflected perpendicularly to the plane of the drawing by an electric field, the element cannot abut the spring 43, and so the spring 43 remains in the solid-line bent position.

In the embodiment shown in FIG. 14, the grate 46 is a rise and fall device. The spring 43b has a top hook 86 and, like the spring of FIG. 13, has for an inoperative position, the bent chain-line position 43c of FIG. 14. In operation, with the element 33 in a flexed position out of the plane of the spring 43b, when grate 46 falls, the hook 86 remains in abutment with the support beam 31 while the spring 43b moves from position 43c into a

straight position (not shown). Should the element 33 move from the flexed position, in which it has been bent at right-angles to the plane of the drawings, into a straight position in which the element 33 is disposed in the plane of the drawing then when grate 46 rises again, spring 43b strikes element 34 and remains in the straight position, so that the hook 86 rises into the solid-line position shown in FIG. 14. A displacing movement for the lifting hooks 14 can be derived from this rise of the hook 86.

In the variant of FIG. 15, the flexural elements of the selector 18 are replaced by tongues or reeds or the like 83 which are actuated by electromagnets 84 and which are adapted to pivot outwardly.

In all the examples, the actuating elements 33, 33a, 84 of the selector 18 are supplied with signals corresponding to the programmed cloth patterning by an electrical or electronic signal generator.

The above used terminology — bendable elongate spring 43 — corresponds to the term "Knickfeder" in the original Swiss application. This latter term means an elongated spring which is not articulated at the ends but only at the middle and this while making use of a compressive or tensile force (FIGS. 2-9, 11, 12) on one or both spring ends or by use of a force imposed transversely on the middle of the spring. The position of rest, i.e., unstressed position, may be an extended position as shown in FIG. 4. The bent position, i.e., stressed position is then as shown in FIG. 3. These positions may also be reversed as shown in FIGS. 13 and 14.

What is claimed is:

1. In a jacquard machine having lifting hooks, a pair of draw knives and means for selectively displacing said lifting hooks into coupling engagement with a respective knife, said means including a bendable spring connected to a respective one of said lifting hooks, said spring being bendable between a first position with said one lifting hook coupled to a respective draw knife and a second position with said one lifting hook uncoupled from said respective draw knife and coupled to the other of said draw knives.

2. In a jacquard machine as set forth in claim 1 wherein said displacing means includes a selector mechanism for selecting said respective lifting hook to be coupled to a respective knife and a transmission mechanism including said spring for moving a selected lifting hook between said positions, said transmission mechanism being connected to said selector mechanism through said spring.

3. In a jacquard machine having lifting hooks; a pair of draw knives;

means for selectively displacing said lifting hooks into coupling engagement with a respective knife, said means including a bendable spring connected to a respective one of said lifting hooks, said spring being bendable between a first position with said one lifting hook coupled to a respective draw knife and a second position with said one lifting hook uncoupled from said respective draw knife, said displacing means further including a selector mechanism for selecting said respective lifting hook to be coupled to a respective knife and a transmission mechanism including said spring for moving a selected lifting hook between said positions, said transmission mechanism being connected to said selector mechanism through said spring, and

a machine part abutting one end of said spring and wherein said spring selectively abuts against said selector mechanism at an opposite end, said machine part and said selector mechanism being movable relative towards each other to bend said spring.

4. In a jacquard machine as set forth in claim 3 wherein said selector mechanism includes a deflectable actuating element for selective movement into and out of the path of said opposite end of said spring.

5. In a jacquard machine as set forth in claim 4 wherein said actuating element has a spring extending therefrom to abut said opposite end of said bendable spring.

6. In a jacquard machine as set forth in claim 3 15 wherein said machine part is a grate having a recess for receiving said end of said spring therein and said end is rolled.

7. In a jacquard machine as set forth in claim 3 further including means for pivoting the top end of said 20 spring during bending.

8. In a jacquard machine as set forth in claim 3 wherein said selector mechanism is a flexural element.

9. In a jacquard machine as set forth in claim 3 25 wherein said transmission mechanism includes a slide block secured to said spring for moving therewith, said respective lifting hook being secured to said slide block to move therewith between said positions.

10. In a jacquard machine as set forth in claim 9 wherein said respective lifting hook is a double lifter 30 having a pair of arms secured in said slide block.

11. In a jacquard machine as set forth in claim 3 wherein said respective lifting hook is a single lifting hook having a pair of hooks positioned for selective engagement with one of said knives.

12. In a jacquard machine as set forth in claim 11 which further includes a stationary support beam and wherein said respective lifting hook has a hook at an upper end to engage said stationary support beam.

13. In a jacquard machine having lifting hooks, a pair 40 of draw knives, and means for selectively displacing said lifting hooks into coupling engagement with a respective knife, said means including a bendable spring connected to a respective one of said lifting hooks, said spring being bendable between a first position with said one lifting hook coupled to a respective draw knife and a second position with said one lifting hook uncoupled from said respective draw knife, said displacing means further including a flexural element for selecting said 45 respective lifting hook to be coupled to a respective knife and a transmission mechanism including said spring for moving a selected lifting hook between said positions, said transmission mechanism being connected to said flexural element through said spring.

14. In a jacquard machine having lifting hooks, a pair 55 of draw knives and means for selectively displacing said lifting hooks into coupling engagement with a respective knife, said means including a bendable spring connected to a respective one of said lifting hooks, said spring being bendable between a first position with said one lifting hook coupled to a respective draw knife and a second position with said one lifting hook uncoupled from said respective draw knife, said displacing means includes a selector mechanism for selecting said 60 respective lifting hook to be coupled to a respective knife and a transmission mechanism including said spring for

moving a selected lifting hook between said positions, said transmission mechanism being connected to said selector mechanism through said spring, said transmission mechanism including a slide block secured to said spring for moving therewith, said respective lifting hook being secured to said slide block to move therewith between said positions.

15. In a jacquard machine as set forth in claim 14 wherein said respective lifting hook is a double lifter 10 having a pair of arms secured in said slide block.

16. A jacquard machine comprising a frame part; lifting hooks; reciprocating draw knives; means for selectively displacing said lifting hooks into coupling engagement with a respective knife, said means at least one spring movable between an extended position and a bent position including a selector mechanism mounted in movable relation relative to said frame part, and said spring being mounted at one end in said frame part and being disposed at the opposite end for movement through a path in said selector mechanism during movement between said positions in response to relative movement between said selector mechanism and said frame part; and

at least one movable control element in said selector mechanism for movement into and out of the path of said opposite end of said spring whereby upon movement of said control element out of said path, said spring is movable into said extended position and upon movement of said control element into said path, said spring is movable into said bent position in response to movement of said frame part and said selector mechanism towards each other.

17. A jacquard machine as set forth in claim 16 wherein said selector mechanism has a slot for receiving said opposite end of said spring and said control element has a spring extending therefrom to close said slot to entry of said opposite end of said spring.

18. A jacquard machine as set forth in claim 16 wherein said control element is a flexural element.

19. A jacquard machine as set forth in claim 16 45 wherein said frame part is a grate having a recess for receiving said one end of said spring therein.

20. A jacquard machine as set forth in claim 16 which further comprises a slide block secured to said spring for moving with said spring in the direction of said positions, and wherein a respective lifting hook is guided within said slide block to move therewith for displacement into or and out of coupling engagement with a respective knife.

21. In a jacquard machine having lifting hooks; a pair of draw knives, each draw knife being movable in a separate vertical path; and means for selectively displacing said hooks into coupling engagement with a respective knife, said means including a bendable spring connected to an intermediate part of a respective one of said lifting hooks, said spring being bendable between a straight position and a bent position, whereby said lifting hook is located in the path of one of said knife with said spring in said straight position and in the path of the other said knife with said spring in said bent position.
